UNITED STATES PATENT OFFICE.

MILLIE W. HILLGARDNER, OF BROOKLYN, NEW YORK.

DESIGN FOR A PENNANT.

56,970.

Specification for Design.

Patented Jan. 25, 1921.

Application filed April 30, 1919. Serial No. 293,853. Term of patent 7 years.

To all whom it may concern:

Be it known that I, MILLIE W. HILLGARDNER, a citizen of the United States, and a resident of the city of New York, borough of Brooklyn, in the county of Kings and State of New York, have invented a new, original, and ornamental Design for a Pennant, of which the following is a specification.

My design comprises a flag, technically known as a guidon, arranged in three divisions, the center bearing the abbreviation

"U. S. A." and the representation of a four-leaf clover, upon two of the leaves of which appear the numerals "2" and "7," and upon the third leaf of which appears the abbreviation "Div."

Reference is to be had to the accompanying drawing in which the figure is a face view of a pennant showing my new design.

I claim:

The ornamental design for a pennant as shown.

MILLIE W. HILLGARDNER.
